UNITED STATES PATENT OFFICE.

WILHELM J. MICHELET, OF SEATTLE, WASHINGTON, ASSIGNOR, BY MESNE ASSIGNMENTS, TO AUTO PULLMAN COMPANY, A CORPORATION OF WASHINGTON.

CONVERTIBLE FURNITURE.

Application filed June 11, 1923. Serial No. 644,613.

To all whom it may concern:

Be it known that I, WILLIAM J. MICHELET, a citizen of the United States, residing at Seattle, in the county of King and State 5 of Washington, have invented certain new and useful Improvements in Convertible Furniture, of which the following is a specification.

The object of this invention, generally, is 10 to provide convertible furniture which is especially designed for use with automobiles.

Specific objects and advantages of the invention will appear in the following description.

The invention consists of devices which are arranged to be detachably mounted upon a running board of an automobile for use as a case to carry cooking utensils, provisions, 20 etc., or capable of use as a table and a stool.

The invention further consists in the novel construction, arrangement and combination of parts hereinafter described and claimed.

In the accompanying drawings,

25 Figure 1 is a perspective view of devices embodying my invention, the table and stool members being arranged to provide a box-like structure, with table legs shown in vertical positions. Fig. 2 is a perspective view 30 of the same, the table and stool members being shown in operative positions. Fig. 3 is a perspective view of the table member with the top and leaf elements thereof arranged in a plane, the leg extensions being 35 partly broken away. Fig. 4 is a view similar to Fig. 3 with the parts differently arranged. Fig. 5 is a perspective view of a portion of one of the table leaf elements. Fig. 6 is a fragmentary plan view of Fig. 4 40 shown partly in section. Fig. 7 is a perspective inverted view of the stool member arranged for use as a luggage carrier. Fig. 8 is a fragmentary front elevational view of the stool member. Fig. 9 is a view similar 45 to Fig. 8 of the table member. Fig. 10 is a sectional view on broken line 10—10 of Fig. 9. Fig. 11 is an underside plan view of a portion of the table member, the legs being shown in their contracted and folded 50 positions.

In carrying out my invention, I provide a table member comprising a top 12 provided adjacent to each of its ends with a pair of legs 13 respectively coupled with each other 55 by bars 14 and connected by hinges 15 (Figs.

9 and 11) with the under side of the top 12.

The bar 14 of each pair of legs is connected with the top by means of a foldable brace which, as shown in Figs. 9, 10, and 11, consists of two bar elements 16 and 17 60 pivotally connected with each other at 18, and at 19 and 20 with the associated leg bar 14 and the top 12, respectively.

Sleeved upon each of the legs 13 is an extension 21 in the nature of a channel bar 65 having a substantially U-shape in horizontal section. A clevis 22 provided at the top of an extension serves to prevent the removal of an extension 21 from its connection with a leg, yet permit the lower ends 70 of the respective extensions being swung outwardly as shown in Fig. 2 to provide a larger base support for the table than what is afforded when the extensions occupy the vertical positions in which they are represented in Fig. 1.

Each of the legs 13 is provided with notches such as 23 which afford shoulder supports engageable upon the upper ends of the respective leg-extensions. The complementary extensions at each end of the table are connected with each other by two links which are pivotally connected together at 24 and to the respective extensions by means 75 of pivot pins 25.

As shown, the referred to links are each 80 comprised of two complimentary bars 26 which are formed to provide spaces therebetween to accommodate the respective legs and the extensions thereof. The bars 26 are 90 furthermore connected by the spaced bolts 26¹ which are disposed to receive therebetween the lower ends of the legs 13 when the extensions are arranged in their relatively spread positions as shown in Fig. 2. One of 95 the bolts 26¹ of each pair of links is also disposed to engage in a notch 27 (Fig. 3) provided in the lower extremity of each leg for the purpose of maintaining either the rear or front extensions in a vertical position as, for instance, the rear extensions denoted by 21^a in Fig. 4, when the front leg extensions, denoted by 21^b in the view referred to, have their lower ends offset as shown. Under such an arrangement (Fig. 4) a bolt 100 105 26¹ of each of the front links engages in the notch 27 of the adjacent leg and thereby serves as a foot support for the front legs and acts to retain the rear leg extensions in 110 vertical positions.

28 and 28¹ represent leaf extensions for the table-top 12 and are provided at one side of each with hooks 29 which are adapted to engage pin elements, such as 30 Figs. 9 and 10, provided in attachments 31 of said top. The leaf extensions of the top may be separably connected to the opposite sides of the latter, as shown in Fig. 3, by means of the inter-connecting hooks and pins.

10 When it is desired, however, to apply both leaves to the front of the top, as shown in Fig. 4, one of the leaves, as 28 for instance, is connected directly to the top by the hook and pin devices above described and securing the leaves together by means of headed coupling bolts 32 inserted in bolt receiving holes of the leaves, said bolts having screw threaded ends which engage in internally threaded sockets such as 33 Fig. 6 provided in the leaf 28.

15 For supporting the leaves I provide bracket bars 34, one at each leg, said bracket bars being pivotally connected adjacent to one end of each by pins 35 to the respective legs and their other ends engaging in recesses, such as 36 Fig. 5, provided in the under sides of the leaves.

20 When the bracket bars 34 are unemployed they are desirably concealed within grooves 37 provided therefor in the respective legs.

25 Included in the invention is a stool, see Figs. 2, 7 and 8, comprising a board 40 which serves as the seat and a pair of leg elements 41 which are hingedly connected by pivot pins 42 to the opposite ends of the seat. The legs at each end are rigidly connected to each other by means of a bar 43.

30 Foldable braces 44, as shown, serve to connect each pair of stool legs 41 with the seat. When the stool is not in use the braces 44 may be folded and the legs 41 brought against the under side of the seat, as represented by dot and dash lines 41¹ in Fig. 8.

35 The stool by being inverted, see Fig. 7, may advantageously be used upon the running board of an automobile to serve as a luggage holder. When thus used the boards or table-leaves 28 and 28¹ are attached to the front stool legs by the provision thereon of studs 45 having relatively large heads which engage in slots, such as 46 Fig. 5, provided in the respective leaves and in plate attachments 47 thereof.

40 The attachments 31 of the table top are provided with apertures 49 to receive the hooks 29 of the leaves 28 and 28¹ when the latter are to be employed as side elements of a box, see Fig. 1, whose ends are afforded by boards 50 which are provided with headed studs 51 which engage in the slots 46 of the leaf attachments 47.

45 The boards 50 and their connections with the leaves 28 and 28¹ serve to retain the latter in vertical parallel positions upon the

table-top 12 which top thereupon serves as the bottom of the box. The cover of the box is provided by the stool seat 40 when laid upon the box sides and ends as shown in Fig. 1. With such a box like arrangement 70 the stool legs 41 are housed within the box, or the legs may be extended upwardly and connected by boards such as 28 and 28¹, as represented in Fig. 7, to afford a luggage holder above the box. 75

For use upon a running board of an automobile, the table legs 13 and the extensions 21 thereof are swung, as denoted by dot and dash B lines in Fig. 1, up against the underside of the member 12. 80

85 While I have described the invention in its construction as now preferred by me, changes in the details may be made within the scope of the following claims without departing from the spirit or sacrificing its advantages.

What I claim, is,—

1. In convertible furniture, a packing case comprising lower, upper and side wall members, said lower and upper members being provided with legs hingedly connected thereto and adapted to be respectively used as a camp table and a camp stool, and means for detachably connecting said lower member to said side members whereby the latter may be employed at the front or back selectively of said lower member to serve as leaf extensions thereto when used as a table. 90

2. In convertible furniture, a table comprising a top, a pair of legs hingedly connected to the underside of said top adjacent the ends of the latter, a horizontal bar rigidly coupling together the legs of each pair thereof, an extension piece slidably and hingedly connected to each of said legs, and link devices connecting the extensions of each pair of legs and engageable with the respective legs for retaining said extensions in vertical and inclined positions selectively. 100

3. In convertible furniture, a table comprising a top, a pair of legs hingedly connected to the underside of said top adjacent the ends of the latter, a horizontal bar rigidly coupling together the legs of each pair thereof, said legs being each provided with a notch at its free end, an extension piece slidably and hingedly connected to each of said legs, and link devices connecting the extensions of each pair of legs and engageable within the notches of the respective legs for retaining said extensions in vertical and inclined positions selectively. 110

4. In convertible furniture, a table having a top member provided with attachments at opposite sides thereof, leaf extensions, and hook elements provided on said extensions and engageable with said attachments for connecting said extensions to said top member in the plane of or at right angles with respect to the top member. 125

5. In convertible furniture, a table having a top member provided with attachments at opposite sides thereof, leaf extensions, hook elements provided on said extensions and engageable with said attachments for connecting said extensions to said top member in the plane of or at right angles with respect to the top member, and means to separably secure said extensions together. 10
6. In convertible furniture, a table having a top, leg members hingedly connected thereto, foldable braces connected at their opposite ends to said top and the respective legs, leaf extensions for said top member, means for detachably connecting said leaf extensions to said top in either vertical or horizontal positions, and means engageable with said extensions for securing the same in vertical positions upon said top, the last 15
- named means cooperating with said extensions to provide the ends and side walls respectively of a box shaped structure whose bottom wall is afforded by said top member. 20
7. Convertible furniture comprising a box shaped structure composed of top, bottom, side walls and end wall elements, said top and bottom elements being provided with legs to serve respectively as stool and table members, said side wall elements being arranged to be detachably connected to said bottom to serve as table leaves. 25
- Signed at Seattle, Washington, this 24 day of May, 1923.

WILHELM J. MICHELET.
